H. N. BERGH

GAME APPARATUS

Filed Jan. 28, 1926

UNITED STATES PATENT OFFICE.

HERMAN N. BERGH, OF ST. PAUL, MINNESOTA.

GAME APPARATUS.

Application filed January 28, 1926. Serial No. 84,433.

My present invention has reference, in its broad aspect, to improvements in game apparatus of the type exemplified by a target and projectile propulsion apparatus for use with the target; and more particularly it is my purpose to provide an improved cross-bow for discharging arrows or shafts at a ball target carried on a support formed to represent the conventional outline of a 10 human body, whereby the game will cause to be inspired in the imagination of a child (or other player) the legend of William Tell, since it was this legendary character who used a cross-bow to shoot an apple from the 15 head of his son.

My target support, in order to represent the son of William Tell is cut or formed in one-piece to conventionally illustrate a human body, and the head portion thereof is 20 provided with a depression for receiving the ball target which is designed to represent the apple of the legend. My cross-bow is formed with a one-piece stock and barrel, the latter being longitudinally grooved to receive an 25 arrow or shaft, and by means of a cross piece through the barrel portion and a bow string carried thereby, the arrow or shaft is discharged at the ball; suitable trigger means being used to release the bow string. The 30 game, so played, has been found to provide a maximum of amusement to a child, with a highly instructive principle underlying the whole proceeding, since the child is not only taught to aim straight, but his curiosity is 35 aroused in the famous characters and incidents of legend and history.

While I have in the present instance defined for the sake of illustration a specific form of my game device it will be understood that I do not desire to limit myself except as may be indicated by the scope of the claims appended hereunto and forming a part of this specification.

In the drawings wherein is illustrated the 45 principal embodiments of my invention:—

Figure 1 is a side elevation of my cross-bow (and when taken with Figure 4 shows the manner of playing my game, the dot and dash line indicating the line of fire),

Figure 2 is a top plan view of my cross-bow,

Figure 3 is a front view of the same,

Figure 4 is a side elevation, or edge view, of my target and support,

Figure 5 is a front view of the target support,

Figure 6 is a view of my shaft or arrow, and

Figure 7 is a fragmentary view of a modified form of the cross piece and bow string 60 of my cross-bow.

In the drawings wherein like characters of reference are used to designate like or similar parts throughout the several views:—

(1) designates the stock, and (2) the barrel of my cross-bow, the same being formed in one piece and of any suitable material. The barrel is longitudinally grooved as at (3) to receive a shaft or arrow (4), and the grip stock (5) is formed with a groove (6) 70 which communicates with the groove (3) and in which is pivotally mounted as at (7) the trigger (8). The bottom of the rear portion of the groove (6) is parallel with the groove in the barrel (2), and the remaining 75 bottom of the groove (6) is inclined to meet the bottom of the groove in the barrel, so that the trigger (8) is limited in its movement by engagement with said portions of the bottom of the groove (6). The grip 80 stock (5) is notched to form a head (9) beneath which one end of the trigger extends. Adapted to engage the head (9) is a flexible 85 bow string (10) which is attached at its ends to the cross piece (11) mounted transversely through an opening in the forward end of the barrel. The shaft or arrow (4) is placed in the groove with its enlarged 90 head (12) adjacent the head (9) over which the bow string is engaged, and upon rocking the trigger the bow string is disengaged 95 from the head (9) to discharge the arrow or shaft.

My target is in the form of a ball (13) which is adapted to be placed in a recess or 95 depression (14) in the target support (15). The target support (15) is formed in one piece having a circular head (16)—in the top of which recess (14) is formed—a neck portion (17), a body (18), and a leg portion (19). The body has lateral extensions (20), and the leg portion has downwardly converging edges (21). The base or bottom edge is notched as at (22) for interlocking engagement in a notch (23) of a cross piece 100 or foot (24). By reference to Figure 5 it will be noted that the support represents conventionally the outlines of a human body; the portion (16) representing the head, (18) the body, lateral extensions (20) the folded 105 arms, and (21) the legs when placed together.

In the modified form shown in Figure 7, a cross piece 11^a is provided which is circular in cross section and is arranged in an opening through the barrel 2^a; the bow 5 string 10^a is in the form of a loop, one end of which is passed over and around the cross piece and then engaged in a notch (25) in the barrel to hold the same in place.

In operation, the target support (15) is 10 set up, with the ball (13) disposed in the recess (14) in the head thereof. This represents the son of William Tell carrying the apple upon his head. Arrows or shafts (4) are discharged at the ball, and the proceeding 15 induces a comparative analogy in the mind of the child and also affords him amusement and lends to accurate archery.

While in the foregoing, there has been 20 illustrated in the drawings and described in the specification such combination and arrangement of elements as constitute the preferred embodiments of my invention, it is nevertheless desired to emphasize the fact that interpretation of the invention should 25 only be conclusive when made in the light of the subjoined claims.

I claim;—

1. A projectile discharge apparatus for use in target games comprising a stock, grip stock, and barrel, the barrel being longitudinally grooved from end to end to receive a projectile, the grip stock being angularly disposed with respect to the barrel and having a groove therein communicating with the groove in the barrel, the rear portion of 35 the bottom of said groove being parallel with the bottom of the groove in the barrel, and the remaining portion of the bottom of the groove in the grip stock being inclined toward the bottom of the groove in the barrel, a trigger pivoted between the walls of 40 said groove in the grip stock and limited in

its rocking movement by engagement with the bottom portions of the groove, said grip stock being formed with a notch at the rear 45 end of the barrel beneath which a portion of the trigger is adapted to operate, a cross piece carried at the forward end of the barrel, and an elastic member carried by the cross piece for discharging the projectile 50 and engageable in extended position over the head formed by the notch in the grip stock.

2. A projectile discharge apparatus for use in target games comprising a single piece 55 of material fashioned to form the stock, grip stock, and barrel of a gun, the barrel being longitudinally grooved from end to end to receive a projectile, the grip stock being angularly disposed with respect to the barrel 60 and having a groove therein communicating with the groove in the barrel, the rear portion of the bottom of said groove being parallel with the bottom of the groove in the barrel, and the remaining portion of the 65 bottom of the groove in the grip stock being inclined toward the bottom of the groove in the barrel, a trigger pivoted intermediate its length between the walls of said groove 70 in the grip stock and limited in its rocking movement by engagement with the bottom portions of the groove, said grip stock being formed with a notch at the rear end of the barrel beneath which the forward end of the trigger is adapted to operate, a cross piece 75 carried at the forward end of the barrel, and an elastic member carried by the cross piece for discharging the projectile and engageable in extended position over the head formed by the notch in the grip stock. 80

In testimony whereof, I affix my signature hereunto.

HERMAN N. BERGH.
